FIG. 5

FIG. 6

INVENTOR:
John H. Schroeder
Nissen & Crane
BY ATTYS.

UNITED STATES PATENT OFFICE.

JOHN H. SCHROEDER, OF CHICAGO, ILLINOIS.

GRAVE CLOSURE.

Application filed September 23, 1925. Serial No. 57,989.

My invention relates to grave closures adapted to be employed during the burial of persons in the earth, and has for one of its objects the provision of means for concealing the opening in the earth while the casket containing the corpse is positioned thereover.

Another object of my invention is the provision of means for simultaneously closing the grave while the casket is being lowered thereinto to conceal the lowering operation from the sight of the mourners.

Other objects of my invention will appear hereinafter, the novel features and combinations being set forth in the appended claims.

15 In the drawings:

Fig. 1 is a top plan view of casket lowering apparatus equipped with a grave concealing device embodying my invention;

Fig. 2 is a sectional end view of a grave concealing device showing an elevational end view of a casket positioned to be lowered into the earth;

Fig. 3 is an elevational end view of casket lowering mechanism equipped with grave concealing apparatus embodying my invention and having a casket thereon in position to be lowered into the grave;

Fig. 4 is an elevational end view of a casket lowering device equipped with grave concealing apparatus and a sectional end view of a grave and a grave box showing a casket positioned in the latter and the concealing apparatus disposed over the opening of the grave;

35 Fig. 5 is a top plan view of casket lowering apparatus equipped with a modified form of the grave concealing device embodying my invention;

Fig. 6 is a sectional end view of the grave concealing device illustrated in Fig. 5 showing an end view of a casket positioned within a grave.

Referring more particularly to Fig. 1 of the drawings, it will be seen that the grave lowering device which is of well known construction comprises a rectangular frame 13 having end bars 5 and 6 and rotatable side bars 7 and 8. The fixed end bars 5 and 6 are secured at their extremities in the dome-shaped posts 9, 10, 11 and 12 which are positioned at each corner of the rectangular frame. The rotatable side bars 7 and 8 are journalled at their extremities in the openings in the dome-shaped posts. The bottom surfaces of the posts 9, 10, 11 and 12 are shown

in Figs. 2, 3 and 4 to be flat and adapted to rest upon the ground at the ends of the grave.

The posts 9, 10, 11 and 12 are provided with gearing, not shown in the drawings, for controlling the rotation of the side bars 7 and 8 to attain a slow and even or constant rate of movement thereof. The foot pedal 42 is connected to the gearing in the dome-shaped post 11 and is adapted to release the gearing to permit rotation of the side bars 7 and 8 and to restrain such gearing from movement when it is desired to stop the rotation of the side bars.

Straps 15 and 16 are securely attached at their ends to the side bars 7 and 8. These straps extend across the length of the frame 13 and are positioned at spaced-apart points intermediate to the ends of the side bars 7 and 8. It will be seen in Fig. 4 that the straps are of sufficient length to lower a casket 17 to the bottom of a grave. When the casket 17 is in its elevated position above the opening of the grave it rests upon the straps 15 and 16 which are drawn tightly across the frame 13 as shown in Figs. 2 and 3 with their end portions coiled on the bars 7 and 8.

The grave closure embodying my invention comprises plates 18 and 19 rigidly fixed at right angles to each other and provided with spring clips 24 and 25 which snap over the bar 8, as shown in Figs. 1 and 2. The plate 18 extends horizontally over substantially one-half of the width of the grave, and the plate 19 is positioned vertically upward. A pair of similar plates 22 and 23 are also rigidly fixed at right angles to each other and are attached to the other side bar 7 by spring clips 20 and 21. The plate 22 extends horizontally across the mouth or opening of the grave and the longitudinal edge 26 thereof lies substantially adjacent the longitudinal edge 27 of the horizontal plate 18. Thus, it should be understood that before the casket is placed on the lowering apparatus and while it rests thereon above the earth the horizontal plates 18 and 22 extend across the opening of the grave and completely conceal the gaping mouth thereof from the view of the mourners.

Ornamental material 28, such as imitation grass, is preferably disposed over the upper surfaces of the plates 18 and 22 and extends upwardly over the inner and outer vertical surfaces of the vertical plates 19 and 23. This mat of ornamental covering material or imitation grass is preferably in the form of

- blankets 45 and 46 which are secured at 47 and 48 respectively, to the vertical walls of the plates 19 and 23 and hang over the latter and into the grave, as shown in Figs. 2 and 3.
- 5 The imitation grass mats 45 and 46 are extended sufficient distances into the grave so as to cover the lower surfaces of the horizontal plates 18 and 22 when they are rotated into the vertical positions shown in Fig. 4.
- 10 Weights 29 and 30 are secured to the free edges of the mats 45, 46 for the purpose of holding the mats in an unwrinkled condition and to counterbalance the weights of the horizontal plates. These weights 29 and 30 counterbalance the plates 18 and 22, and the clips 20, 21, 24 and 25 hold the vertical plates 19 and 23 respectively in upright positions and prevent inward rotation thereof while the casket is above the ground.
- 15 In order that the device may be employed to conceal graves of different sizes the plates 18, 19, 22 and 23 respectively are provided with telescoping sections 31, 32, 33 and 34. These sections may be extended or retracted 20 to correspond with the dimensions of the grave so that no portion of the opening thereof will be left uncovered. Pins 35 are preferably provided to hold the telescoping sections in their adjusted position and may 25 be inserted in openings or holes in the tongues 36, 37, 38 and 39, of the telescoping sections.
- To facilitate transportation of the covering apparatus the plates 18 and 22 are each divided into two sections which are joined by 30 hinges 40 and 41, respectively. These sections may be folded substantially together to produce a compact arrangement that may be lifted and loaded into a vehicle with little difficulty.
- 35 In operation, the casket is placed upon the straps 15 and 16 while the covering apparatus is in the position shown in Fig. 1. The casket is supported entirely by the straps which are coiled, as shown in Fig. 2, upon the bars 7 and 8. When the foot pedal 42 is pressed it 40 releases the gearing in the dome-shaped post 11 and the casket to slowly descend into the grave. This downward movement of the casket causes the ends of the straps 15 and 50 16 to be uncoiled resulting in an inward rotation of the bars 7 and 8. The foot pedal 42, when in its uppermost position, is adapted to lock the gearing in the dome 11 so that the bars 7 and 8 will be restrained from rotation. While the foot lever is held in its lowermost position the gearing in the dome 55 11 is unlocked and the bars are free to be rotated by the weight of the casket and by the downward movement thereof.
- 60 As the casket descends the bottom thereof engages the top of the horizontal plates 18 and 22 and causes the grave concealing apparatus to be rotated inwardly. Stops 43 and 44 are preferably secured to each of the 65 ends of the plates 19 and 23, as shown in Fig.

1, to engage the fixed end bars when these plates reach their horizontal positions. These stops are illustrated at 43' and 44' of Fig. 1 by dotted lines in engagement with the end bars 5 and 6. As casket descends the 70 vertical plates 19 and 23 are rotated inwardly to cover the opening or mouth of the grave so that the lowering operation will not be visible to the mourners. By the time the casket has reached the dotted line position, shown at 75 49 in Fig. 4, the plates 19 and 23 are extended over the opening of the grave and thus further downward movement of the casket is rendered invisible.

The straps 15 and 16 may be moved from beneath the casket after it has been lowered to the full line position shown in Fig. 4. This removal may be accomplished by permitting the casket to rest upon the cleats 45 within the grave box 50 so that the straps may be easily slipped over and around the ends of the casket. The lever or crank 14 may then be employed to recoil or wind up and lift the straps from within the grave.

The spring clips, 20, 21, 24 and 25 are arranged so that the open side thereof is directed downwardly when the plates are in the position shown in Fig. 4 so that the plates may be lifted upwardly to disconnect them from the bars of the lowering device. This arrangement is preferably provided so that it will not be necessary to disassemble or alter any of the elements of the lowering apparatus in order to attach or detach the covering members.

The form of my invention disclosed in Figs. 5 and 6 comprises a pair of cloth or fabric covered cover plates 50 and 51 mounted on a grave lowering apparatus identical to the apparatus shown in Figs. 1, 2, 3 and 4. This form of my invention employs flat counter-weighted covering members adapted to be disposed over the opening of a grave while a casket is placed thereover for the purpose of obscuring the gaping mouth of such grave from the view of the mourners.

Referring more particularly to Fig. 5 of the drawings, it will be seen that the cover plates 50 and 51 comprise frames 52 and 53 respectively and that such frames are provided with covering material such as imitation grass 58. The frames 52 and 53 are provided with longitudinal members 59 and 59' respectively which are of sufficient weight to counterbalance the weight of the frames 52 and 53 and the weight of the covering material 58 thereon. A series of arms 60, 61, 62, 63, 64 and 65 are secured at right angles to the counterweight 59 and extend horizontally over the opening of the grave. A similar series of arms 60', 61', 62', 63', 64' and 65' are secured at right angles to the other counterweight 59' in registration with the arms 60, 61, 62, 63, 64 and 65 of the frame 53.

Spring clips 54 and 55 are attached to the 130

counterweight or longitudinal side member 59 of the frame 52 at the ends thereof. These spring clips are adapted to rotatably support the entire covering member 50 on the side bar 7' of the lowering apparatus. A pair of similar clips 56 and 57 are attached to the counterweight 59' for the purpose of mounting the cover plate 51 on the side bar 8' of the lowering apparatus. Braces 66 are attached to each of the clips 54, 55, 56, and 57 and their respective counterweights, by means of bolts 67 and 68. These braces secure the clips in place and are adapted to support much of the weight of the cover plates 15 when the latter are rotated into the vertical position shown by dotted lines at 69 and 70.

Straps 15' and 16' are shown in Fig. 5 and are for the purpose of supporting a casket in the manner disclosed in Figs. 1, 2, 3 and 4. 20 The arms 61 and 62 of the frame 52 are positioned one on each side and immediately adjacent the strap 16' and the arms 63 and 64 are positioned one on each side and immediately adjacent the strap 5'. These arms are 25 provided with short flexible fingers 71 which preferably comprise thin spring steel. The fingers 71 extend beneath the straps and across the slot 72 between the two arms 61 and 62 for the purpose of supporting the covering material 58 and to hold the latter in place so as to form an apparently continuous layer or sheet. The covering material 58 is preferably tacked to the fingers 71 as shown at 30 73 in Fig. 5. This arrangement permits the 35 covering plates to be returned to their horizontal position after the casket has been lowered to the dotted line position shown at 74 in Fig. 6, in a manner hereinafter described.

In operation, the casket is placed upon the 40 straps 15' and 16' while the covering device is in the position shown in Fig. 5. The casket is supported entirely by the straps which are coiled upon the bars 7' and 8'. When the foot pedal 42 is pressed it releases the gearing 45 in the dome-shaped post or housing 11' and permits the casket to slowly descend into the grave. While the foot lever is held in its lowermost position the gearing in the housing 11' is unlocked and the braces are free to be 50 rotated by the weight of the casket and by the downward movement thereof.

As the casket descends the bottom thereof engages the top of the horizontal covering plates 50 and 51 and causes the grave concealing apparatus to be rotated downwardly to the dotted line position shown in Fig. 6. These plates are held in substantially vertical position while the casket descends and are then rotated back again into a horizontal position by the counterweights 59 and 59'. The flexible fingers 71 permit the plates 50 and 51 to be rotated upwardly into a horizontal position while the straps 15' and 16' depend into the grave as shown in Fig. 6. The flexible 65 fingers are adapted to bend sufficiently to al-

low the straps to pass through the slot 72. When the plates have reached their horizontal position the flexible fingers resume their original shape and stretch the covering material 58 over the gap 72 thus affording an 70 apparently continuous blanket of imitation grass. The edges of the plates 51 and 56 may be permitted to overlap as shown at 75 in Fig. 6 for the purpose of adapting the device to graves of various widths. 75

Obviously those skilled in the art may make various changes in the details and arrangement of parts without departing from the spirit and scope of the invention as defined by the claims hereto appended, and it is 80 therefore desired not to be restricted to the precise construction herein disclosed.

Having thus fully described and shown an embodiment of the invention what is desired to be secured by Letters Patent of the 85 United States is:

1. The combination with a casket lowering device comprising rotatable bars, of means supported by said bars for covering a grave, and means secured to said covering means 90 comprising spring clips for gripping said bars to cause rotation of said covering means in unison therewith during a portion of one rotation thereof, said clips being adapted to permit continued rotation of said bars while 95 said covering means are held at rest.

2. The combination with a casket lowering device comprising rotatable members, of means supported by said rotatable members for covering a grave, stops on said covering 100 means to engage said lowering device when said covering means are in a predetermined position, and detachable clipping means secured to said covering means adapted to grip said rotatable member for rotating said 105 covering means in unison therewith.

3. The combination of means for lowering a casket into a grave, and covering means comprising pairs of plates fixed at right angles to each other, one of the plates of each 110 of said pairs of plates being adapted to cover half of the mouth of said grave while the casket is retained thereover, the other plate of each of said pairs of plates being adapted to cover the mouth of the grave after the 115 casket is lowered thereinto.

4. The combination with casket lowering mechanism for lowering a casket into a grave, of means for concealing the opening of said grave comprising horizontal plates extending beneath said casket when the latter is positioned above the opening of said grave, plates fixed at right angles to said horizontal plates and extending upwardly therefrom, and means for automatically causing said 120 horizontal plates to rotate from beneath said casket as the latter is lowered and to cause said upright plates to rotate inwardly to cover the opening of said grave after the casket has been lowered thereinto. 125 130

5. A grave closure for concealing the opening of a grave while the casket is placed thereover and during the lowering of said casket comprising horizontal plates mounted along the longitudinal sides of said grave and extending across the opening thereof beneath said casket, vertical plates rigidly fixed at right angles to said horizontal plates, and mounting means for supporting said pairs of

fixed plates adapted to permit said horizontal plates to be rotated from beneath said casket while said vertical plates are moved to a position thereover. 10

In testimony whereof I have signed my name to this specification on this 21st day of ¹⁵ September, A. D. 1925.

JOHN H. SCHROEDER.
